UNITED STATES PATENT OFFICE

GLENN F. COUCH, OF ROCHESTER, NEW YORK, ASSIGNOR TO THE SYMINGTON COMPANY, OF NEW YORK, N. Y., A CORPORATION OF MARYLAND

DRAFT RIGGING

Application filed April 23, 1928. Serial No. 272,285.

This invention relates to draft rigging, and more particularly to cheek plates adapted to be secured to the sides of associated center sills for improving the strength of connection 5 between said sills and draft rigging positioned therebetween.

The principal object of my invention, generally considered, is to provide draft rigging cheek plates with inwardly extending abut- 10 ment portions formed either integral with or as bushings in the cheek plate slots and embracing the associated rear key for improving the strength of connection by decreasing the effective span and increasing the bearing 15 area for said key.

Another object of my invention is to provide a cheek plate for railway draft rigging doubly slotted and formed with flanges defining the slots therein with the flange sur- 20 rounding the rear slot being extended inwardly beyond the flange surrounding the forward slot for embracing the associated rear key and decreasing the effective span of 25 said key, while at the same time increasing the bearing area.

A further object of my invention is to provide a railway draft rigging with doubly slotted cheek plates connected to associated sills, draft keys extending through the slots 30 in said cheek plates and supporting an associated coupler, yoke and front follower, the rear slots in said cheek plates being formed with extensions between upper and lower portions of said yoke, said extensions being 35 continued close to the front follower for decreasing the effective span for the associated rear key, whereby the strength of connection is increased.

Other objects and advantages of the invention relating to the particular arrangement 40 and construction of the various parts will become apparent as the description proceeds.

Referring to the drawings illustrating my invention, the scope whereof is defined by the appended claims:

Figure 1 is a partial plan and partial horizontal section of a portion of the car under-frame showing draft rigging and associated cheek plates embodying my invention.

Figure 2 is a vertical longitudinal sec-

tional view of the rigging shown in Figure 1 with the coupler and front follower omitted, the associated yoke being shown only dia- grammatically.

Figures 3 and 4 are views corresponding, 55 respectively, to Figures 1 and 2, but showing a modification.

Referring to the drawings in detail, like parts being designated by like reference characters, and first considering the embodiment 60 of my invention illustrated in Figures 1 and 2, the center sills or draft sills of a car are designated by the reference character 1, the forward ends thereof being connected by a combined striking casting and sill tie mem- 65 ber 2, and intermediate portions thereof being connected by any ordinary or desired form of backstop casting 3. The sills 1, and more particularly the vertical web portions 4 thereof, are slotted, as indicated at 5, the 70 slot in one sill registering with that in the other. Attached to said sills, preferably by rivets 6 around the slotted portions 5 thereof, is a pair of cheek plates 7, in the present embodiment each being provided with a plu- 75 rality or pair of slots 8 and 9, the forward slots 8 receiving the front key 10 and the rear slots 9 receiving the rear key 11. As is usual, the front key 10 supports the stem of

the associated coupler 12 and the front ends 80 of the associated yoke 13, the rear key 11 supporting the front follower or movable draft gear element 14 and extending through slotted portions in the yoke 13. The rear end of the yoke 13 abuts the backstop 3 and 85 is supported in any desired manner, as by means of angular clips 15 attached to the center sills 1. The associated cushioning mechanism 16 is indicated diagrammatically by dot and dash line and may be supported in any 90 desired manner as by means of a carrier iron 17 connected to the lower flanges of the sills 1 by means of bolts or the like, as illustrated, and extending between the front follower 14 and an associated rear follower 18.

In order to increase the bearing areas for the keys 10 and 11, the slots 8 and 9 in the cheek plates are defined or bordered by flanges 19 and 20, respectively, said flanges 95 extending outwardly beyond the webs 20 of 100

the cheek plates which are connected to the outer sides of the webs 4 of the sills for providing relatively great bearing area for the ends of the associated draft keys, as well as increasing the strength of said cheek plates.

- 5 The flanges 19 and 20 extend inwardly toward the associated yoke 13 and engage the correspondingly slotted portions in the sill webs for increasing the strength of connection therewith and taking the strain off the rivets 6. The rear ends of the rear slots 9 are reinforced by intermediate webs 21 extending between the flanges 20 and the extension 22 filling the slot 5 in the associated sill which is of sufficient length to receive the same. The adjacent ends of the front and rear slotted portions are similarly rigidified by the intermediate web or gusset 23.

It will be understood that the rear key is what directly transmits the draft forces to the cheek plates and sills of the car, said forces passing from the coupler to the front key, yoke, rear follower, cushioning mechanism, front follower and from there through the rear key to the cheek plates and sills of the car. In order to decrease the effective span for the rear key 11, as well as increase the bearing area provided for said key, the flanges 20 are extended inwardly toward each other between spaced portions 24 and 25 of the yoke 13 so that the inner ends thereof are closely adjacent the front follower 14, said extensions in the present embodiment only being at the front and rear ends of the slots 9 and tapering off to merge into the planes of the inner faces of the center sills 1, as indicated at 26, between the front and rear ends of said slots. This construction decreases the span for the rear key by an amount approximating double the thickness of the arms of the yoke and this decrease in span, as will be understood, is quite material, especially as it is accompanied by the corresponding increase in bearing area for the key. 45 Although the extensions between the upper and lower portions 24 and 25 of the yoke are illustrated as only at the front and rear ends of the slots 9, it will be understood that I do not wish to be limited to this showing as said extensions may be continued the full length of the slots, if desired, and the yoke arms correspondingly spaced.

Referring now to the embodiment of my invention illustrated in Figures 3 and 4, a construction is there disclosed which accomplishes the same result as in the previous embodiment, the sills 1a being correspondingly slotted and having connected thereto cheek plates 7a, as in the previous embodiment, said cheek plates being slotted, as indicated at 8a and 9a for supporting front and rear keys 10a and 11a, respectively, which in turn support the coupler 12a, the yoke 13a, and the front follower 14a.

65 In the present embodiment the yoke 13a is

different from that of the previous embodiment in that instead of comprising vertically spaced loop portions connected at their forward ends only, it involves a single loop portion formed with relatively large slots 27 adjacent the forward ends thereof, the forward end of the slots receiving the front key 10a and the rear ends of said slots being correspondingly enlarged to receive the inner ends of bushings 28 which may be cast in place or otherwise securely attached in the rear slots 9a in the cheek plates 7a, the inner ends of said bushings extending toward each other to closely approach the front follower 14a and function in a manner similar to the extensions of the flanges 20 on the cheek plates of the previous embodiment.

As contra distinguished from the flanged extensions on the cheek plates of the previous embodiment, the bushings are extended a uniform amount at their inner sides and the slots 27 in the yoke as therefore necessarily considerably enlarged to receive said extensions. It will be understood, however, that the extensions on the bushings 28 may correspond with the integral extensions from the cheek plates of the first embodiment, if desired. The yoke slots are continued beyond the rear ends of the bushings 28 an amount sufficient to allow for the compression of the associated draft gear 16a. In the present embodiment the front ends of the bushings 28 are shown flanged beyond the correspondingly slotted portions of the cheek plates 7a, as indicated at 29, said flanged portion tapering to merge with the plane of the outer face of the cheek plate flanges 19a and 20a a short distance rearwardly of the front end of the slot in said bushings. Except as specifically described in connection with the present embodiment, the same may correspond with that of the first embodiment.

From the foregoing disclosure it will be apparent that I have devised reinforcing cheek plates for draft or center sills of railway cars which cooperate with the associated rear key for improving the strength of connection by not only decreasing the span provided for said key but increasing the bearing area for the ends of the same. The yoke used with such cheek plates may involve either vertically spaced loop portions connected at their front ends or a loop portion formed with unusually large slots at the front ends thereof. It is only necessary to provide the extended abutment portions around the rear slots in the cheek plates, said abutment portions being either at the front and rear ends of said slots or surrounding said slots for the full length thereof. Said extensions may be either integral with the cheek plates, as illustrated in the first embodiment, or formed as bushings securely connected to the cheek plates in any desired manner.

Having thus described my invention, what I claim is:

1. In railway draft rigging, in combination with center sills formed with elongated slots therein, cheek plates each having a plurality of alined slots and connected to the outer sides of said sills, a draft key extending through registering slots in said cheek plates, a horizontal yoke slotted for receiving said key, a follower disposed between the arms of said yoke, slotted for receiving and supported on said key, flanges projecting laterally from opposite faces of said cheek plates, the sill adjacent portions of said flanges engaging the edges of the slotted portions of said sills, and portions extending inwardly beyond said sills in the slotted portions of the yoke close to the follower to increase the bearing area and shorten the span of said key.

2. In railway draft rigging, in combination with slotted center sills, cheek plates correspondingly slotted and positioned so that the slots in one register with those in the other, a draft key extending through oppositely disposed slots in said cheek plates, a slotted yoke associated with said key, a slotted front follower disposed between the arms of said yoke and mounted on said key, and inward projections on said cheek plates extending in the slotted portions of said yoke close to the follower and embracing said key for increasing the strength thereof by shortening the effective span.

3. In railway draft rigging, in combination with center sills with elongated slots therein, cheek plates each having a plurality of alined slots and positioned so that the slots in one register with those in the other, flanges surrounding the slotted portions in said cheek plates and engaging the edges of the slots in the sills, the forward and rearward end portions of the rear slots in said cheek plates being formed with flanges extending inwardly beyond the upper and lower flanged portions thereof for engaging an associated draft key and increasing the strength thereof by decreasing the effective span, the depth of said extensions being such that they are receivable between portions of a horizontal yoke normally spaced to receive a front follower-supporting key.

4. A cheek plate adapted for connection to a draft sill and comprising a web having horizontally alined forward and rearward slots therein, adapted for receiving associated coupler-connecting and draft gear element-supporting keys, respectively, a plurality of flanges projecting laterally from the opposite faces of said plate and defining the edges of said slots, the flanges extending from the inner face of said cheek plate around the rearward slot being continued beyond the flange surrounding the forward slot to form elongated stop means for the draft

gear element-supporting key for decreasing the distance between the abutment portions for said key, whereby the effective strength of connection between the draft gear and the associated sill is increased.

5. In railway draft rigging, in combination with center sills formed with elongated slots therein, cheek plates each having a slot and connected to the sills, a draft key extending through the slots in said cheek plates, a horizontal yoke with vertically spaced portions of each arm extending above and below said key, a movable element of associated draft mechanism disposed between the arms of said yoke and connected to the cheek plates by said key, and flanges projecting laterally from the inner faces of said cheek plates between said spaced portions of the yoke close to the movable element to increase the key bearing area and shorten the span thereof.

6. In railway draft rigging, in combination with center sills having elongated slots, slotted cheek plates connected to said sills, said slots being considerably larger than the normal slots in railway draft gear cheek plates, bushings received in said enlarged slots in said cheek plates and provided with slots of normal size for receiving a front follower draft key, said bushings extending inwardly toward one another and providing space therebetween just sufficient to receive an associated front follower, a draft key extending through the slots in said bushings, a follower supported on said key, and a yoke embracing said follower and formed with slots enlarged to receive those portions of the bushings extended toward said follower.

7. A cheek plate adapted for connection to a draft sill and comprising a web with an enlarged slot therein, a bushing securely connected in said slot and extended laterally from the inner face of said plate, said bushing having a slot therein of normal size for receiving a follower supporting draft key, said bushing extending from the inner face of the cheek plate an amount approximately equivalent to the normal thickness of a yoke arm so that it is adapted to closely approach an associated follower for decreasing the distance between the abutment portions for the associated key, whereby the effective strength of connection between the follower and associated sill is increased.

8. A cheek plate adapted for connection to a draft sill and comprising a web having a plurality of horizontally aligned slots, a plurality of flanges projecting laterally from the opposite face of said plate and defining the edges of said slots, the flanges extending from the plate around the rear slot being more widely spaced than the flanges around the forward slot, and a bushing securely seated between the flanges around the rear slot and extended beyond the inner edges of said flanges an amount substantially correspond-

ing with the normal thickness of a draft yoke arm, said bushing having a slot therein of normal size for receiving an associated horizontal draft key.

5 9. A cheek plate adapted for connection to a draft sill and comprising a web with a horizontally disposed slot therein adapted for receiving a draft gear element supporting key, flanges projecting from the inner face 10 of said plate and defining the edges of said slot, the portions of said flanges adjacent the ends of said slot extending beyond the remainder of said flanges an amount approximating the normal thickness of an arm of 15 a horizontal yoke, the depth of said extensions corresponding with the normal spacing between upper and lower portions of said yoke arm for receiving a draft key, said extensions forming elongated stop means for said key 20 for decreasing the distance between the key abutment portions whereby the effective strength of connection between the draft gear element and the associated sill is increased.

25 In testimony whereof I affix my signature.
GLENN F. COUCH.
